Patented Nov. 25, 1919.

UNITED STATES PATENT OFFICE.

FREDERICK H. HEBERT, OF NASHUA, NEW HAMPSHIRE.

ATTACHMENT FOR LOOMS.

1,323,186.

Specification of Letters Patent. Patented Nov. 25, 1919.

Application filed March 26, 1919. Serial No. 285,227.

To all whom it may concern:

Be it known that I, FREDERICK H. HEBERT, a citizen of the United States, residing at Nashua, in the county of Hillsborough and 5 State of New Hampshire, have invented new and useful Improvements in Attachments for Looms, of which the following is a specification.

My present invention pertains to looms, 10 and it contemplates the provision in a loom of means whereby should the lug strap or picker stick break, the shuttle will be caused to operate in such a manner as to immediately stop operation of the machinery of the 15 loom, and hence preclude the breaking of parts in the organized mechanism.

The invention will be fully understood from the following claims and description when the same are read in connection with 20 the drawing accompanying and forming part of this specification in which:

Figure 1, illustrates my novel means for stopping a loom when occasion demands and further shows the shuttle at one extreme of 25 its movement in the loom and its relation to the boxer wheel of the loom stopping mechanism.

Fig. 2, illustrates in detail the position the shuttle assumes when an accident to the 30 picker stick or lug strap takes place, and exactly how said shuttle operates on the boxer wheel to cause stopping of the loom.

Fig. 3, illustrates in detail the loom stopping mechanism.

Similar numerals of reference designate 35 corresponding parts in all of the views of the drawings.

The shuttle 6, is of the ordinary well known construction and operates in the conventional manner in the loom.

Experience has demonstrated that because of the constant striking of the shuttle against the picker stick, the picker stick or lug strap, after a short period of use become 45 broken or otherwise inoperative and when this breaking takes place, a large amount of damage is caused to the loom and its appurtenances. In order to immediately stop operation of the loom, I provide 50 the novel means illustrated and comprising a boxer wheel 1, of concave form and constructed of metal, wood, fiber, leather or the like, and said wheel is secured by an axle in the arms 20, that extends 55 downwardly on either side wheel. The said arms merge into a single solid piece 23 and

further merge into the sliding arm 2. As clearly shown in Fig. 2, the arm 2 is provided near its upper end with an aperture through which the upper end of a knock-off 60 rod 3, extends and is securely held with respect to the arm 2.

In order to provide a support for the arm 2 and its appurtenances, I furnish a base 5 having the straps 10 and said straps serve 65 to secure the sliding arm 2 to said base 5.

In order to confine the rod 3, in a slidable manner on the base 5, I provide a clip 12 at a point slightly below the center of said base and the said clip 12 is provided with an aperture at a point adjacent to where it is secured to the base 5 and through which the rod 3 passes.

As clearly shown by the drawings, the spring 4 is interposed between and abuts at 75 one end against a collar 16 of the arm 2 and at the opposite end against one of the straps 10 of the base 5; said spring encircling the arm 2 at all times, and being provided for the purpose of always forcing the boxer 80 wheel rearwardly against the shuttle, when said shuttle through breaking of the lug strap or picker stick is caused to ride over and rest upon the boxer wheel.

The rod 3 is bent outwardly as indicated 85 by 13, so as to engage the shipper release arm 7 to operate the shipper 8.

In the practical operation of my invention, when the picker stick or lug strap breaks, the shuttle 6 will be caused to ride 90 over and rest upon the boxer wheel 1 and when this takes place, the arm 2 will be forced forwardly by the weight of the shuttle and the spring 4 will be placed under tension. Because of its connection to 95 the arm 2, the rod 3 will likewise be forced forwardly and this will force the portion 13 of said arm against the shipper arm 7 forcing the same forwardly. In view of its construction, the outer end of the arm 7 will 100 thus be forced rearwardly and such movement will tend to release the shipper 8 and thus immediately stop operation of the loom; it being well known that the shipper is exactly what its name implies,—i. e., a 105 device (for which I make no claim) that ships or shifts the belt that applies power to a loom from its operative to its inoperative positions.

The device is simple in construction and 110 will because of its positive operation prevent imperfect transfer which is brought

about by breaking of the picker stick and lug strap and the jumping of the bobbin occasioned thereby, is inoperative except in case of mishap, may be operated by any size shuttle because of the coiled spring 4, which tends to always force the boxer wheel against the shuttle, and will manifestly save yarn and bobbins because of the device precluding the breaking of the bobbin and its 10 appurtenances.

Having described my invention what I claim and desire to secure by Letters Patent is—

1. In a device for the purpose set forth, 15 the combination of a base, an arm slidable in said base, a boxer wheel mounted at one end of the arm, a movable rod secured at one end to the arm and slidable therewith, a clip mounted on the base and capable of 20 holding the rod in slidable manner to said base, and means for forcing the boxer wheel rearwardly and comprising a coiled spring that encircles the arm and abutting at one 25 end against said arm and at its opposite end against a portion of the base; the rod being bent outwardly at its foremost end and capable of bearing against a shipper arm when said rod is forced forwardly.

2. In a loom, the combination of a shuttle, 30 smash preventing means arranged adjacent the shuttle; said means comprising a boxer wheel of concave form, an axle on which the wheel rotates, forwardly extending portions in which the axle is mounted, and an 35 arm formed integral with said portions and extending forwardly therefrom and being slightly reduced in diameter to produce a collar at a point in the length of said arm, an aperture provided near the rear end of 40 the arm, a rod secured at its rear end in said aperture and being provided at its forward end with a bent portion, a base having straps at each end thereof that form retaining means for the first-named arm, a clip 45 secured to the base and constructed in substantial L-shape form and having an aperture through which one end of the rod

passes, and a coiled spring encircling the arm and abutting at its rear end against the collar of the arm and abutting at its forward 50 end against the foremost strap of the base portion to force the boxer wheel rearwardly.

3. In an attachment for looms, the combination of a shuttle, a concave boxer wheel arranged adjacent to the shuttle, a slidable 55 arm having a bearing in its rear end in which the wheel rotates, a collar former intermediate said arm by diminishing the diameter thereof at a point midway the length thereof, a base having means at its 60 rear and forward ends in which the arm slides, a rod secured at its rear end to the arm and slidable therewith; a bent end portion formed at the forward end of the rod, a clip secured to the base and engaging the 65 rod to prevent casual displacement thereof, and a spring encircling the arm and abutting at one end against the collar of said arm and at its opposite end against the forward part of the means of the base in which 70 the arm slides; said spring tending to force the boxer wheel rearwardly.

4. In a device of the character set forth, 75 the combination of a wheel, a shuttle capable of bearing on said wheel, an arm secured to the wheel and capable of horizontal movement therewith, a base having rear and forward guideways in which the arm moves, a clip secured to the base, a rod engaged at its rear end by the arm and at its 80 forward end by the clip; said rod having a forwardly bent end portion, a coiled spring encircling the arm whereby when the wheel is forced forwardly the rod will bear against shifting means of a loom to prevent 85 further operation of the loom.

In testimony whereof I have hereunto set my hand in presence of two subscribing witnesses.

FREDERICK H. HEBERT.
